US0D1036545S

(12) **United States Design Patent** (10) **Patent No.:** **US D1,036,545 S**
(45) **Date of Patent:** **** Jul. 23, 2024**

(54) **MAGNETIC ERASABLE MARKER**

(71) Applicant: **Wenhuan Lin**, Zhejiang (CN)

(72) Inventor: **Wenhuan Lin**, Zhejiang (CN)

(**) Term: **15 Years**

(21) Appl. No.: **29/853,485**

(22) Filed: **Sep. 15, 2022**

(30) **Foreign Application Priority Data**

Sep. 6, 2022 (CN) 202230587416.3

(51) **LOC (14) Cl.** **19-06**

(52) **U.S. Cl.**

USPC **D19/163**

(58) **Field of Classification Search**

USPC D14/411, 480.3, 264; D19/115, 117, D19/163, 164, 168, 170, 173, 174, 177, D19/178, 179, 186, 196, 197, 199, 204, D19/901, 902, 906, 914, 916, 924, 929, D19/932, 934, 139, 166, 167, 171, 121, D19/130, 183, 175, 127; D28/7, 9, 76, D28/77, 86, 88, 89; D27/101, 146, 162, D27/163; D24/113; D26/37, 38, 49; 15/443; D20/23; D8/104; D3/220

CPC B43K 7/005; B43K 29/00; C09D 10/00; G06F 3/0383; G11B 3/48

(57) **CLAIM**

The ornamental design for a magnetic erasable marker, as shown and described.

DESCRIPTION

FIG. 1 is a perspective view of a first embodiment of the magnetic erasable marker showing my new design; FIG. 2 is a perspective view thereof from another angle; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; FIG. 8 is a bottom plan view thereof; FIG. 9 is a perspective view of a second embodiment of the magnetic erasable marker showing my new design; FIG. 10 is a perspective view of FIG. 9 from another angle; FIG. 11 is a front elevational view of FIG. 9; FIG. 12 is a rear elevational view of FIG. 9; FIG. 13 is a left side elevational view of FIG. 9; FIG. 14 is a right side elevational view of FIG. 9; FIG. 15 is a top plan view of FIG. 9; and, FIG. 16 is a bottom plan view of FIG. 9.
